SEPARATING SOLID PARTICLES

Sydney Edward Thacker Ewing and Joseph Leonard Willey, Johannesburg, Transvaal, Union of South Africa

Application November 1, 1933, Serial No. 696,260
In Union of South Africa November 3, 1932

13 Claims. (Cl. 209—429)

The present invention relates to the separation of solid particles, such as particles of ground ore and the like, according to their different settling tendencies in a fluid.

According to this invention, the mixed material is supported upon a flexible sheet in which is generated a procession of waves without displacement of the sheet as a whole. The waves are such that each wave trough carries a charge of the material which remains within and is transported by its trough as the latter moves forward. Owing to the sheet being stationary in the direction of procession, the transportation is accompanied by a rolling movement of the trough charge over itself; whereby its particles are agitated and constantly re-exposed at the surface. The trough charges or some of them are meanwhile exposed to the influence of a fluid under conditions such that the particles of lesser settling tendency are removed from the trough charge. The particles remaining in the trough charge may be removed by the wave movement out of the influence of the fluid.

The invention is illustrated in the accompanying drawings in which:—

Figure I is a perspective view of a mechanical classifier embodying the invention.

Figure II shows a portion of the flexible sheet, in plan.

Figures III and IV illustrate a method of manufacturing the flexible sheet of the classifier.

Figure V is a longitudinal elevation of a table concentrator with parts broken away.

Figure VI is an end view sectioned on VI—VI

Figure V.

Figure VII is a half plan of Figure V.

The apparatus shown in Figure I resembles the well known mechanical classifiers in that it comprises a tank 2 into which pulp to be separated is fed from a supply conduit 3; the liquid carrying slime (or the more buoyant particles) passing away by way of the overflow lip 4; whilst the sand constituent of the pulp, which settles through the liquid, is worked up the sloping floor 5 and discharged at the upper end 6 thereof into the launder 7.

The modification of such apparatus effected by the present invention resides in the sloping floor and the manner in which the sand is worked up it.

The floor consists of flexible sheet material 5, such as sheet rubber, secured in a water-tight manner to the walls of the tank. For this purpose its longitudinal edges 8 are shown as clamped between cleats 9 on the side walls 10. Its lower end 11 is turned up and secured to the

boards 12 so that said boards and said turned up end form the third wall of the tank, the turned up end providing a flexible lower portion of said third wall on which the waves are initiated.

The flexible sheet 5 is supported, and the waves 13, 14 are produced in it by a series of rollers 15 on which the sheet freely rests and which extend across the sheet. Said rollers are spaced apart and translated, by being journaled in brackets 16 extending from the links of a pair of endless chains 17 mounted on sprockets 18; the latter being rotated in the direction indicated by the arrow A to cause those rollers which are carried by the upper spans of the chains, to travel up the incline.

The support for said rollers is provided by a pair of inclined tracks 20. On these tracks run pairs of track rollers 21, one pair for each roller 15. Said track rollers 21 are, like the rollers 15, mounted in the brackets 16. The rollers 15 rest freely upon the track rollers: their journal holes in the brackets 16 being elongated to permit this.

The sheet 5 is extended upward well beyond the tank proper and its upper end 6 is fixed to the chute 19.

In order to permit the waves 13, 14 to be produced without stretching the rubber and without restraint by the clamped edges 8 of the sheet, the sheet is formed with a central zone 22 which is as long as the developed length of the series of waves and which is laterally defined by lines 23. The extreme longitudinal edges 8 of the sheet, which are secured to the side walls 10, are as long as said side walls and thus considerably shorter than the central zone 22; and said edges 8 are connected to the central zone by the two longitudinally disposed lateral zones 24 which are such as to afford the transition between the length of the central zone and the length of the side edges.

Figures III and IV illustrate a method of manufacturing a sheet of this form.

Two pieces 24a of flexible sheet material are cut to annular form such that their outer edges 25 are equal in length to the developed length of the zone 22, and their inner edges 26 approximate to an arc 26a which is equal in length to the edges 8, the distance between the arc 26a and the edge 26 being the width of the material required for attachment to the side wall.

A rectangular piece 22a of sheet rubber is cut equal in width to the central zone 22, that is, the distance between the lines 23 and equal in length to the developed length of the central zone. The annular pieces 24a are secured one at each side of the rectangle 22a and with their long edges 25

united to the longitudinal edges of the rectangle; to which they are equal. Such securing of the edges is conveniently done by providing a drum 27, the radius of which is equal to the radius of the arc 25 and the width of which is equal to the width of the piece 22a. The latter piece is wrapped around the cylindrical surface of the drum and the annular pieces 23a are held against the respective end faces of the drum. The corners 28 of the drum are rounded to a small radius to enable the edges of the pieces 24a and 22a to be butted against one another. Said edges are united by cementing or the like; and the completed assembly, being removed from the drum, becomes the sheet 5; the piece 22a constituting the central zone 22 and the pieces 24a constituting the lateral zones 24.

In order that the waves may effectively transport the material lying in their troughs 14, it is necessary for the wave fronts 29 to be distinctly steeper than the angle of repose of the material on the rubber. To enable such steep wave fronts to be produced, the central zone 22 is made of such length that when the wave crests 13 are shaped by the rollers 15, the troughs 14 are distinctly baggy. The steepening is assisted, and undesirable depth of the troughs avoided by causing the lower ends of the troughs to rest on fixed decking 30 so that each trough has a flat base from which the wave front 29 rises at a sharp angle.

For the purpose of retaining this baggy formation of the troughs and to prevent bodily displacement of the loose central zone, it is necessary that the rollers 15 should not be merely pushed beneath the sheet but should have a true rolling motion against the lower face thereof. Due to the extra length of the central zone 22 over the direct length of the floor, the rollers have so to rotate that while their translational displacement is equal to the length of the floor, their peripheral displacement equals the developed length of the central zone 22. This is brought about by making the diameter of their treads 31, which rest upon the track rollers 21, less than the diameter of the roller surfaces in the ratio of the direct length of the sheet to the developed length of its central zone 22, in other words in the same ratio as the arcs 25 and 26a.

In operation the tank contains pulp up to the level indicated by the line 32, which is the trace of the pulp surface on the wall 10. Fresh pulp being fed from launder 3, and the chain and roller mechanism being in operation, the pulp is kept in a state of agitation which causes slime or the lighter material to remain in suspension in the liquid. Liquid is constantly displaced by the incoming pulp and flows away over lip 4, carrying slime with it.

The waves on the sheet begin at the lower end of the floor due to the travelling roller 15 coming into contact with the floor at that point; and thus travel in a constant succession to the upper end 6 of the floor, where they disappear owing to the rollers 15 passing around the upper sprockets and so away from the floor. The sand constituent of the pulp settles in those wave troughs 14 which are for the time being submerged in the tank 2; and by its weight it emphasizes the steep fronted form of the waves. Each trough charge is carried up the inclined floor by reason of the translational movement of the waves and is eventually discharged into launder 7.

Since the floor surface is substantially without movement in the direction of its length,

while the trough charges travel over it in that direction, said charges are rolled over the surface. In this way they are kept in a state of agitation which prevents their compacting; and fresh surfaces of them are constantly exposed. This permits slime to continue to separate from the sand and to enter into suspension in the pulp while the charges are within the tank. It also renders the charges which have passed out of the tank readily susceptible to washing by wash water delivered for instance from spray nozzles 33. Such wash water tends to flow along the troughs transversely to the length of the floor and so reach the side channels 34 at the junction of the floor with the side walls 10, down which side channels it is free to flow back to the tank without re-contaminating the lower trough charges. In this way the waved floor tends to clean separation of sand and slime. It will be observed that mechanism subject to wear is wholly external of the tank and not in contact with the pulp in any way. It is thus protected against the rapid wear which occurs at the joints and other vulnerable parts of mechanism when working submerged in pulp.

The concentrating table shown in Figures V to VII comprises an apron 35 secured along a central line to a longitudinal bar 36 supported by hangers 37 from the cross members 38 of the frame of the table. The table is, in the example shown, duplicated on each side of said central line.

Except where it is secured to the bar 36, the apron is unattached and both the wings of it rest loosely on the upper span of an endless series of spaced rollers 39 carried by the chains 40 which in turn are supported and moved by the sprockets 41.

The rollers 39 form in the apron a series of waves each consisting of a crest 42 and a trough 43, extending transversely to the length of the apron.

The troughs preferably increase in depth from the centre of the table towards each longitudinal edge thereof; and the apron is pre-formed to enable it to take this form without being stretched. That is to say each wing of the apron is cut as a part of an annulus of which the inner edge is equal to the length of the bar 36 and its outer edge equal in length to the developed length of the outer edges 44 of the apron. Said annular pieces are secured to the bar 36 by their short edges. The troughs of the waves are, as in the classifier, baggy and loose; similarly, the rollers 39 are so rotated on their own axes and tapered towards their mid points that they lift and lower the apron loosely without transporting it longitudinally.

For this purpose there are provided the track rollers 45 mounted on the chain brackets 46 which carry the rollers 39 and running on the tracks 47. Fast with each roller 45 is a friction wheel 48 of larger diameter which engages with and rotates a tread 49 on the adjacent roller 39. In this way transportation of the waves, longitudinally of the apron of solid material resting on the trough, is assured.

The mixed material to be treated is fed onto the central portion of the apron, at the end thereof from which the wave motion commences; for instance from a feed box 50. The material falls into the troughs 35 in succession as they come before the feed box and the advancing waves tend to carry the trough charges to the farther end 51 of the apron. Meanwhile the

trough charges are turned over and constantly exposed to fluid flowing from the centre of the table towards its edges 44. Such flowing fluid may be jets of air, if the material is dry; or water when the material is in the form of pulp. The pulp may be originally fed in a sufficiently dilute condition to itself provide the required lateral flow of water; or additional wash water may be supplied as from nozzles 52. The trough charges are thus given a second motion along the troughs outwardly, due to the flowing fluid assisted by the slope of the troughs. The specifically lighter and less valuable gangue material is most influenced in this way and is passed off the apron at an early stage of the operation, into say a waste launder 53. The specifically heavier constituents of the pulp most resist the washing and gravitational action and so are finally discharged into a concentrate launder 54 situated at or towards the end 51 of the table. An intermediate grade of material may be collected in a middlings launder 55.

We claim:—

1. Apparatus for separating solid particles, comprising a flexible sheet which is so anchored as to be immovable as a whole and which is of non-uniform developed linear extent in the direction of the translation of the rollers, means to produce a succession of material-transporting and agitating waves in said sheet comprising a series of spaced rollers on which the sheet loosely rests, means to translate them transversely of their length successively beneath the sheet, the diametral dimension of the several rollers being at any cross section proportionate to the developed linear extent of the sheet at the line of contact therewith of said section, and means additional to the sheet and the translating means to rotate said rollers about their own axes, simultaneously with their translation, at a speed proportionate to the diameter at any section and the linear translation of said section so that they have only rolling contact with the sheet, together with means to subject material in the wave troughs to fluid in motion so as to remove particles of lesser settling tendency from the troughs.

2. Apparatus for separating solid particles, comprising a fixed framework, a flexible sheet including a relatively short longitudinal zone fixed to said framework, and including also a relatively long longitudinal zone so arranged that it occupies the same rectilinear extent as the short zone and thus assumes a baggy condition, means to produce a succession of material-transporting and agitating waves moving continuously in one direction only longitudinally in said relatively long zone of the sheet, means to cause deposition of material in the troughs of said waves, and means to subject material in the wave troughs to fluid in motion.

3. Apparatus for separating solid particles comprising tank walls providing an overflow lip, an inclined flexible sheet constituting the floor of the tank and extending upward above the overflow lip, means to produce in said sheet a succession of material-transporting and agitating waves moving longitudinally and upwardly of the sheet, and means to introduce pulp to be separated into the tank.

4. Apparatus for separating solid particles comprising tank walls providing an overflow lip, an inclined flexible sheet constituting the floor of the tank and extending upward above the

overflow lip, means to produce in said sheet a succession of material-transporting and agitating waves moving longitudinally and upwardly of the sheet, means to introduce pulp to be separated into the tank, and means for discharging wash liquid into the wave troughs above the overflow lip. 5

5. Apparatus for separating solid particles, comprising tank walls providing an overflow lip, an inclined flexible sheet constituting the floor of the tank and extending upward beyond the overflow lip, said sheet having relatively short longitudinal edge zones fixed to the tank structure and a relatively long central longitudinal zone puckered to occupy the same length as the edge portions, means contacting with the relatively long central zone of the sheet to produce a series of upwardly moving material-transporting and agitating waves therein, and means to introduce pulp into the tank. 10 15 20

6. Apparatus as claimed in claim 11, which includes means to feed wash liquid to the troughs above the overflow lip, and in which the flexible sheet provides longitudinal drainage channels at the junction of the central zone with the edge zones. 25

7. Apparatus for separating solid particles, comprising tank walls providing an overflow lip, an inclined flexible sheet constituting the floor of the tank, and extending upward beyond the overflow lip, said sheet having relatively short longitudinal edge zones fixed to straight portions of the tank structure, said sheet also having a central longitudinal zone of greater developed length than the edge zones and occupying the same direct length as the latter, a series of cylindrical rollers moving beneath the central zone to form a series of upwardly moving waves therein, means for positively rotating said rollers on their individual axes so that they have rolling contact with the sheet, means so supporting the troughs of the waves as to cause the waves to be steep-fronted, and means to introduce the pulp into the tank. 30 35 40

8. Apparatus for separating solid particles, comprising a horizontally disposed flexible sheet which is anchored against bodily movement, means to feed material to be separated onto a corner at one end of the sheet, means to produce in the sheet a series of material-transporting and agitating waves moving away from said end and extending transversely of the sheet to an edge thereof, and a series of stationary launders arranged for selectively receiving material discharged from the edging of the sheet distant from the feeding corner. 45 50 55

9. Apparatus for separating solid particles, comprising a horizontally disposed flexible sheet which is anchored against bodily movement, means to feed material to be separated onto a corner at one end of the sheet, means to produce in the sheet a series of material-transporting and agitating waves moving away from said end and extending transversely of the sheet to an edge thereof, means to subject material in the wave troughs to a material-separating fluid current which is about parallel with the waves, and a series of stationary launders arranged for selectively receiving material discharged from the edging of the sheet distant from the feeding corner. 60 65 70

10. Apparatus for separating solid particles, comprising a framework, a flexible sheet varying transversely as regards its longitudinal developed length, the shortest developed length being ar- 75

ranged in a horizontal plane and fixed to the framework, means to produce in said sheet a series of transverse waves increasing in depth from said shortest length to an edge of the sheet and moving in one direction only longitudinally of the sheet, means to feed material to be separated onto the sheet at one end of said shortest length and a series of stationary launders arranged for selectively receiving material discharged from the edging of the sheet distant from the feed point.

11. Apparatus for separating solid particles, comprising a framework, a flexible sheet varying transversely as regards its longitudinal developed length, the shortest developed length being arranged in a horizontal plane and fixed to the framework, a series of conical rollers supporting and moving beneath the sheet in one direction only and forming therein a series of transverse waves increasing in depth from said shortest length to an edge of the sheet and moving in said one direction only longitudinally of the sheet, means to feed material to be separated onto the sheet at one end of said shortest length and a series of stationary launders arranged for selectively receiving material discharged from the edging of the sheet distant from the feed point.

12. Apparatus for separating solid particles, comprising a framework, a horizontally disposed flexible sheet anchored to the framework against

bodily movement, means to feed material to be separated onto a corner of the sheet at one end thereof distant from an edge, a series of rollers arranged transversely to and supporting the sheet so as to form a series of transverse waves therein, means for traversing said rollers continuously in one direction beneath the sheet, means additional to the sheet and the translating means for rotating them on their individual axis so that they have rolling contact with the sheet and a series of stationary launders arranged for selectively receiving material discharged from the edging of the sheet distant from the feed point.

13. Apparatus for separating solid particles, comprising a flexible sheet, a pair of endless chains extending longitudinally of the sheet, means to propel the chains, brackets extending from links of the chain, sheet supporting rollers carried by said brackets and so supporting the sheet as to form therein a series of material-transporting and agitating waves, a fixed track, and track rollers carried by the brackets and rolling on said track as the chains are propelled, said track rollers rotating the sheet supporting rollers at a peripheral speed greater than their own.
